UNITED STATES PATENT OFFICE.

CARL MUEHLEISEN, OF BERLIN, GERMANY, ASSIGNOR TO MERGENTHALER LINOTYPE COMPANY, A CORPORATION OF NEW YORK.

TYPOGRAPHICAL COMPOSING-MACHINE.

1,138,135.

Specification of Letters Patent.

Patented May 4, 1915.

Application filed December 26, 1914. Serial No. 879,191.

To all whom it may concern:

Be it known that I, CARL MUEHLEISEN, a citizen of the United States of America, residing at Chausseestrasse 23, Berlin, N. 4, 5 in the Empire of Germany, have invented new and useful Improvements in Typographical Composing-Machines, of which the following is a specification.

This invention relates to typographical 10 composing machines such as those known commercially under the trade mark "Linotype", and particularly to those which are provided with a plurality of superposed magazines, and with a supporting frame for 15 each magazine. When it has been desired to remove a magazine from such a machine, as hitherto constructed, it has been necessary to remove, at the same time, the respective magazine-supporting frame, each magazine 20 and supporting frame being dealt with as a single entity. According to the present invention, the removal of the magazines is greatly facilitated, and heavier and stronger magazine-supporting frames are rendered 25 possible, by making each magazine independent of its supporting frame, and by providing suitable connections between each magazine and the respective supporting frame as well as between the several frames, 30 so that each magazine and each frame can be taken out of the machine separately.

The invention is hereinafter, for convenience, described in connection with a machine provided with two superposed magazines, and the accompanying drawing shows sufficient of such a machine to illustrate the application thereto of the present improvements, Figure 1 being an elevation, and Fig. 2, a plan thereof.

40 Referring to the drawing, *a* and *b* are the two magazines (the lower one, *a*, being shown in operative position); and *c*, *d*, are the respective supporting frames for the lower and upper magazines. The lower supporting frame *c* is provided with rollers *f* which bear upon the cams *e*, by means of which the magazines are adjusted to their operative positions. Each magazine is held to its frame by a rib *g* extending fore and aft thereof and engaging in a corresponding groove in the frame, and is prevented from sliding downward by a cross-bar *h* engaging suitable recesses in the frame. To remove a magazine, independently of its supporting 45 frame, its lower end is raised until the

cross-bar *h* is free from the respective frame, and the magazine is then slid downward with its rib *g* in the groove of the said frame. To prevent accidental displacement of the magazines, hooks *i* and *j* are provided, 50 pivotally attached to the respective supporting frame and adapted to engage with the respective studs *j*, *j'*, on the appropriate magazine, which hooks and studs must be disengaged before removal of a magazine.

The upper supporting frame *d* is provided, on each side, near its upper end, with a depending yoke *k*, which straddles a stud *m* projecting from the side of the lower supporting frame *c*, thus forming an easily detachable connection between the two frames, and at the same time serving to prevent the said upper frame from sliding down along the top surface of the lower magazine *a*, on which it rests. A further connection between the two frames *c*, *d*, which prevents any vertical displacement of the upper supporting frame *d*, relatively to the lower one, is afforded by the engagement 70 of hooks *n*, pivoted to the lower frame *c*, with studs *o* projecting from the sides of the said upper frame. When it is desired to remove the supporting frame *d* from the machine, after the magazine *b* has been removed, it is only necessary to disengage the last-mentioned hooks *n* from their studs *o*, and raise the frame until the yokes *k* are clear of the studs *m*. After the frame *d* has been taken away, the magazine *a* can be 75 removed from the machine, independently of its frame *c*, in the same manner as that described above in connection with the magazine *b* in respect of its frame *d*.

Having described my invention, I declare 80 that what I claim and desire to secure by Letters Patent is:

1. In a typographical composing machine, the combination of two superposed magazines, two corresponding supporting frames therefor, the supporting frame for the upper magazine resting directly upon and supported wholly by the underlying magazine, and detachable means for connecting the several parts separably together; whereby 100 said parts may be held together as a unitary structure and whereby each may be removed separately from the machine.

2. In a typographical composing machine, the combination of two superposed maga- 110

2
zines, two corresponding supporting frames therefor, the supporting frame for the upper magazine resting directly upon and supported wholly by the underlying magazine, 5 and detachable connections between the two supporting frames whereby the upper one is held in place in the machine and is capable of independent removal therefrom at will.

3. In a typographical machine, the combination of two superposed magazines, and 10 two corresponding supporting frames therefor, the upper frame resting directly upon and supported wholly by the underlying magazine and being provided at its opposite 15 sides with depending arms extending past the upper magazine and detachably connected to the lower supporting frame, for the purpose described.

4. In a typographical machine, the combination of two superposed magazines, two 20 corresponding supporting frames therefor, the upper supporting frame resting upon and supported wholly by the underlying magazine, detachable connections between 25 the two supporting frames whereby they are held together against longitudinal displacement, and a locking latch connected to one of the supporting frames and arranged in engagement with the other, and serving to 30 prevent their relative vertical displacement.

5. In a typographical machine, the combination with two superposed magazines, two 35 corresponding supporting frames therefor, connections between the two supporting frames whereby they are held against relative longitudinal displacement, and detachable connections between each magazine and its corresponding supporting frame, whereby they are also held against relative longi-

tudinal displacement, of a locking latch connected to one of the supporting frames and arranged in engagement with the other to prevent their relative vertical displacement, and a locking latch connected to each of the supporting frames and arranged in engagement with the corresponding magazine to prevent their relative vertical displacement. 40

6. In a typographical composing machine, the combination of a plurality of superposed magazines, a separate magazine-supporting frame for each magazine, mutually engaging studs and yokes on the magazine-supporting frames adapted to prevent relative movement of the said frames in parallel planes, and mutually engaging hooks and 50 studs on those frames adapted to prevent relative movement thereof in a direction perpendicular to the aforesaid planes. 55

7. In a typographical composing machine, the combination of a plurality of superposed magazines, a separate magazine-supporting frame for each magazine, mutually engaging studs and hooks on the magazines and frames for the purpose of connecting and disconnecting them, mutually engaging 60 studs and yokes on the magazine-supporting frames adapted to prevent relative movement of the said frames in parallel planes, and mutually engaging hooks and studs on those frames adapted to prevent relative 65 movement thereof in a direction perpendicular to the aforesaid planes. 70

In witness whereof I have hereunto set my hand in the presence of two witnesses.

CARL MUEHLEISEN.
